UNITED STATES PATENT OFFICE.

ARTHUR H. FOWLER, OF ZANESVILLE, OHIO.

SECTIONAL WATER-TUBE BOILER.

SPECIFICATION forming part of Letters Patent No. 233,228, dated October 12, 1880.

Application filed February 10, 1880.

To all whom it may concern:

Be it known that I, ARTHUR H. FOWLER, of Zanesville, in the county of Muskingum and State of Ohio, have invented a new and useful Improvement in Sectional Water-Tube Boilers; and I do hereby declare that the following is a full, clear, and exact description of the same.

My invention relates to that class of boilers in which the cylinders are arranged in pairs, one above the other, and are connected with water-tubes which are exposed to the action of the flames.

The invention consists in a certain inclined arrangement of these boilers, in forming the cylinders and their connection-tubes in sections; in the arrangement of the water-tubes in relation to the grate, so as to cause the flame and gases to break up and pass around and among the tubes; in making the tubes bent to overcome the effects of the rust caused by exposure; in an arrangement of duplicate boilers with an intermediate combustion-chamber and air-pipes, and in certain other details of construction hereinafter fully set forth, and specifically indicated in the claims.

In the drawings accompanying this specification, Figure 1 is a section of the furnace from front to rear on line *xx* of Fig. 2. Fig. 2 represents the front of the boiler, partly in elevation and partly in section, with the front wall removed. Fig. 3 shows an elevation in part of the front wall and in part of the bridge-wall. Figs. 4 and 5 represent details enlarged, hereinafter fully explained.

The main object of the invention is to produce a boiler in which the steam is generated in a series of tubes, and in which these tubes are arranged as nearly as possible in a vertical position to prevent the lodgment of sediment.

The boiler, as represented in the drawings, consists, essentially, of upper and lower cylinders *A A* and connecting-tubes *B B*. The cylinders are made preferably of from twenty to thirty-six inches in diameter, but must in all cases be large enough for a person to enter and clean. The upper cylinder stands in advance of the lower, to which it is connected a distance equal to one-half the length of the grate-bars. They are placed crosswise of the furnace or at right angles with the side of the

boiler, and they are extended sufficiently to reach through the side walls of the brick setting. One end of each cylinder is provided with an ordinary man-hole. The upper cylinder may be set from six to fifteen feet above the lower, to which it is connected at the ends by tubes *C C*, made from six to twelve inches in diameter, to provide for the downflow of the water. These tubes *C C* are set so far out on the ends that the side walls of the setting enclose them, as shown clearly in Fig. 2, so as to keep them sufficiently cool, and thereby provide for the downward flowing of the water.

As shown clearly in Figs. 1 and 2, a series of tubes, *B B*, connect the upper and lower cylinders, and cross at a slight angle of inclination the fire-space, through which rise the products of combustion. These tubes are bent at the ends, so as to spread out and afford room for the action of the products of combustion, and at the same time to enter the shells or cylinders at the proper angle, or on lines radial to said cylinders. The bending of these tubes thus affords better connection with the shells, and at the same time counteracts the otherwise injurious effects of the expansion and contraction of the tubes under variations of temperature.

The lower cylinder, it will be observed, is partially embedded in the brick-work on one side of the grate and is not fully exposed to the direct heat of the furnace.

As shown also in the drawings, the cylinders above described may be arranged in pairs, each pair being provided with a full set of small bent tubes and large end tubes. The second pair (marked in the drawings *A' A'*) are set back of the first, and may, if preferred, be inclined at the same angle or may be set vertical. The two pairs are connected at the top by a large pipe, as shown at *a*, (or by steam-drum,) attached to the flanges upon the cylinder, as shown at *b*. A pipe-connection (not shown in the drawings) is also required between the two lower cylinders.

The front and back walls rise vertical, as shown at *d d*, to a point above the level of the fire-door, from which point they incline toward the top cylinders at about the same angle as that at which the cylinders are set. I thus obtain room for a large furnace, which is

so inclined as to force all the flame toward the boiler-tubes, and also bring the tubes to a certain extent over the fire; but at the same time I have a receptacle for deposits to accumulate in below or removed from the direct or greatest heat of the fires, these deposits descending freely in the nearly vertical tubes and lodging in the lower cylinders.

Between the front and rear of the pairs of cylinders I place a bridge-wall, K, which rises to a point a little distance below the line of the lower set of the upper cylinders, as shown in Fig. 1, leaving a combustion-chamber between its upper edge and the outer wall. This bridge-wall is formed with an interior zigzag passage, by which air is admitted to a space, h, which extends the entire length of the wall and permits the air to pass through a narrow opening in the casting H. This casting extends the entire length of the bridge-wall, and has its ends anchored in the side walls. The air is admitted into the passages or chambers k from the outside through the opening E, and is highly heated by reason of its retarded passage back and forward through the series of passages or chambers, and escapes in a thin sheet extending the entire length of the wall into the combustion-chamber. The smoke-exit is shown in Fig. 1 at L.

30 The air may be supplied by a natural draft or by forcing, as may be required. The casting H is made in such a form as to support the bridge-wall when built in an inclined position.

By the arrangement above described an exceedingly desirable point is gained. All the flames and hot gases are compelled to pass in a divided condition as they rise between and among the water-tubes, and thus give off their heat to the water. After passing, as they rise between and among the first series of tubes, they are brought together again in the combustion-chamber. They there meet the thin stream of heated air entering the full width of the furnace, thus supplying oxygen to complete the combustion of any unconsumed carbon. As the air has been highly heated in its passage, there is no tendency to lower the temperature of the products of combustion by its admission. The products of combustion, after the admission of air to the combustion-chamber, pass downward around and among the back series of tubes, entirely around the lower rear cylinder, and thence up the chimney.

I provide at each corner of the brick-setting a corner plate in section in the form of an angle-iron, extending from bottom to top, and bolted at regular intervals by strong bolts passing on the four faces, and of sufficient strength to firmly bind the brick-work. Instead of the large fire-front I use a cast-iron frame for fire and ash doors, as shown at m m in Fig. 1.

For a certain class of boilers the cylinders heretofore described may be made of cast-steel of high ductility and tensile strength. I contemplate making them in sections, the upper

corresponding with the lower, and connected thereto by a proper number of bent tubes. The ends of these sections are beaded, as shown at p, made male and female, and turned off truly to make a joint by the use of a copper gasket.

The sections may be made of any length to carry any desired number of these water-tubes that may be demanded by the exigencies of the case, this form of boiler being designed for use in those regions where it is difficult to transport a large boiler entire, and where these sections may be carried and put together after reaching their destination.

The sections may be united by a sufficient number of hollow bolts extending from head to head, and drawing all the joints tightly together. I use hollow bolts to provide for a less proportionate expansion than the sections which they unite. One of these bolts is shown enlarged in Fig. 4 at D. They are also represented by the same letter in Fig. 2. They are made open at the ends, so that the currents of air may pass freely through them and keep them cooler than if made solid. Instead of this mode of joining the sections that may be used which is shown in Fig. 5, in which the sections are united by bolts passing through flanges turned inwardly to avoid exposure to the fire. The joint in this case may be made tight by calking or in any of the well-known ways.

Boilers made upon either of the sectional plans may be suspended by a set of columns and girders, as shown at F G, so that they may be hung up entirely independent of the brick-work. When, however, the problem of difficulty of transportation does not come in, I design to make these cylinders of boiler-iron in the usual manner, extending from wall to wall, and support them by a simple column under each end of the upper cylinders.

Having thus described my invention, what I claim as new, and desire to secure by Letters Patent, is—

1. A sectional water-tube boiler composed of upper and lower sectional cylinders, opposite sections being connected by the bent water-tubes, as set forth.

2. A sectional water-tube boiler consisting of upper and lower cylinders connected by bent water-tubes arranged within the combustion-chamber, the tubes and upper cylinder being inclined over the grate and exposed to the products of combustion, as and for the purpose set forth.

3. In combination with the front and rear boilers, and with connections between them, the intermediate chamber and the air-inlet, as set forth.

4. The combination of the front and rear boilers, the combustion-chamber, and the fire-bridge wall, with its air-heating passage, as set forth.

5. In combination with the inclined boilers arranged in chambers as described in relation

to each other and to the grate, the inclined walls, as and for the purposes set forth.

6. In combination with the sectional cylinders, the hollow connecting-rods, open at the ends to the outer air, as set forth.

7. The combination of the upper and lower cylinders, connected by the bent tubes and extending across the combustion-chamber from wall to wall, with the water-pipes C C, inclosed

within the walls, connecting said upper and lower cylinders, as set forth.

In testimony whereof I have signed my name to this specification in the presence of two subscribing witnesses.

ARTHUR H. FOWLER.
